UNITED STATES PATENT OFFICE.

ELSA DIENEMAN, OF NEW YORK, N. Y.

DESIGN FOR A LADY'S HAND-BAG.

48,776.

Specification for Design.

Patented Mar. 28, 1916.

Application filed December 8, 1915. Serial No. 65,837. Term of patent 3½ years.

To all whom it may concern:

Be it known that I, ELSA DIENEMAN, a subject of the Emperor of Germany, and a resident of the city of New York, borough of Brooklyn, in the county of Kings and State of New York, have invented a new, original, and ornamental Design for Ladies' Hand-Bags, of which the following is a specification, reference being had to the accompanying drawing, forming a part thereof.

The figure is a perspective view showing my new design.

The article of manufacture constituting the subject matter of this specification comprises the formation of a handbag simulating a dressed doll having a wide or flaring

skirt A constituting the bag proper, while the bust portion B of the doll constitutes the top or closure for the bag. The design also includes the provision of one or more ribbon-like hangers C serving not only as suspending means for carrying the handbag, but also designed to give the doll a proper, natural, and ornamental upright position, not tipping over by its own weight.

I claim:—

The ornamental design for ladies' handbag, as shown and described.

ELSA DIENEMAN.
